The ornamental design for a female connector for surface mounting, as shown and described.

DESCRIPTION

FIG. 1 is a front, right side, bottom perspective view of a female connector for surface mounting;

FIG. 2 is a front view thereof;

FIG. 3 is a rear view thereof;

FIG. 4 is a plan view thereof;

FIG. 5 is a bottom view thereof;

FIG. 6 is a right side view thereof;

FIG. 7 is an enlarged vertical sectional view thereof, taken along the line VII-VII of FIG. 2; and,

FIG. 8 is an enlarged vertical sectional view thereof, taken along the line VIII-VIII of FIG. 2.

FIG.1

FIG.2

FIG.3

FIG.4

FIG.5

FIG.6

FIG. 7

FIG. 8

UNITED STATES PATENT AND TRADEMARK OFFICE
CERTIFICATE OF CORRECTION

PATENT NO. : Des. 351,137
DATED : October 4, 1994
INVENTOR(S) : Kiyoshi Sato

It is certified that error appears in the above-identified patent and that said Letters Patent is hereby corrected as shown below:

On the title page:

Item 30, Foreign Application Priority Data, should read
Aug. 31, 1992 [JP] Japan.....4-25789.

Signed and Sealed this
Eleventh Day of April, 1995
